UNITED STATES PATENT OFFICE.

GEORGE ALEXANDER WETTENGEL, OF ST. LOUIS, MISSOURI.

LADLE-STOPPER-OPERATING MECHANISM.

1,207,251.

Specification of Letters Patent.

Patented Dec. 5, 1916.

Application filed October 20, 1915. Serial No. 56,905.

To all whom it may concern:

Be it known that I, GEORGE A. WETTENGEL, citizen of the United States, residing at St. Louis, in the State of Missouri, have 5 invented certain new and useful Improvements in Ladle-Stopper-Operating Mechanism; and I do hereby declare the following to be a full, clear, and exact description of the invention, such as will enable others 10 skilled in the art to which it appertains to make and use the same.

My invention consists in the novel features hereinafter described, reference being had to the accompanying drawings in which 15 I have illustrated one form of my invention selected by me for purposes of illustration, and the said invention is fully disclosed in the following description and claims.

Referring to the said drawings, Figure 1 20 is a diagrammatic view of the interior of a portion of a steel mill showing in elevation my ladle and improved means for operating the stopper of the same. Fig. 2 is a vertical sectional view of a portion of the ladle and 25 stopper, the stopper operating means being in elevation. Fig. 3 is a front view of a portion of the ladle and the mechanism for operating the stopper of the same. Fig. 4 is a vertical sectional view of the fluid cylinder 30 used for raising and lowering the ladle stopper. Fig. 5 is a view taken on line 5, Fig. 3. Fig. 6 is a vertical sectional view of a modified form of fluid cylinder.

In order that my invention may be clearly 35 understood, I deem it desirable to briefly describe the present manual means and method of operating the stopper of a ladle for molten steel. In teeming, say a sixty ton ladle of molten steel, the ladle which is 40 provided with a refractory lining, stopper and stopper operating mechanism, is supported and conveyed from the furnace to the molds, and from mold to mold by a crane, which is provided with a trolley and by 45 which the ladle is carried and also raised or lowered as required. The ladle which has previously been internally heated, is placed under the tapping spout of the furnace by the crane, and the furnace is then tapped, 50 the molten metal flowing out and filling the ladle. The ladle is then raised and carried over one of a series of cast iron molds and the ladleman standing on a platform adjacent the molds, operates a lever while his 55 helper removes a key which clamps the stopper mechanism in its closed position and

which key has been placed in position prior to tapping the furnace to prevent the surging metal from opening the stopper. The ladleman lowers the lever controlling the 60 stopper mechanism, thereby raising the stopper allowing the metal to enter the mold, until the latter is filled and he then raises the lever and lowers the stopper to close the ladle aperture when the mold is 65 filled. The ladle is then conveyed from mold to mold which are filled consecutively until the ladle is empty. This method is known as top casting and while other methods have been used, they need not be described. 70

It has been found in practice that the disadvantages of operating a ladle stopper in the manner above described, are numerous, owing to the extreme heat of the molten metal and its liability to erupt and scatter 75 over the operators. It will therefore be apparent, that the ladleman and his helper standing on the platform adjacent the molds, occupy very dangerous positions, owing to the fact that the gases escaping 80 from the metal while the mold is filling, keep the metal in violent motion and eruption, frequently causes a spray of hot metal to fall upon and burn the operators. Again many operators are fatally burned by the 85 molten metal escaping from a ladle, overturning when a rope, chain, hook or other part of the hoisting mechanism breaks, which is liable to occur at any time. It also occasionally happens, after partly emptying 90 the ladle, that the metal will violently react, the escaping gases throwing liquid metal to the roof of the building, often burning off the trolley wires, destroying the trolley motor and rendering it extremely dangerous 95 for the operators, it being necessary to cover them with wet sacks to keep their clothes from igniting. A further and very serious objection resides in the fact that not infrequently the stopper will only partially close 100 the nozzle opening, due to imperfect construction, thereby allowing a stream of metal to escape when the nozzle is supposed to have been closed. Again the nozzle occasionally breaks, owing to the sudden expansion, when the hot metal strikes it, thereby causing a leak, so that while the ladle is being conveyed from mold to mold, the liquid metal from a leaky nozzle striking the top edges of the molds, splashes upon the operators and frequently burns them seriously. It 105 is to overcome these objections and obviate

the necessity of employing ladlemen and their assistants, that I have devised my improved stopper operating mechanism. With my improvements, the operation of the ladle 5 stopper is entirely under the control of the craneman, who is always a sufficient distance away from the ladle and molds to insure his safety.

Referring more particularly to the drawings, 1 represents the side walls of a portion of a steel mill; 2 the crane tracks; 3 the crane; 4 the crane trolley; 5 the ladle cable; 6 the ladle and 7 the crane cage, all of which are of the usual construction and form no 15 part of my present invention.

In teeming, the ladle 6, which has previously been internally heated, is placed under the tapping spout 8 of the furnace (not shown) by the crane 3. The furnace is 20 then tapped, allowing the molten metal to flow out of the spout and fill the ladle. The ladle is now carried by the crane trolley over one of a series of cast iron molds 9 and the ladle stopper, hereinafter described, is 25 raised to permit the molten metal to flow from the ladle and fill said mold.

My improvements consist in mechanical means for raising and lowering the ladle stopper to fill the molds 9 and to this end 30 my invention comprises a bracket 10, secured to the exterior of the ladle by any suitable means and provided with hook-shaped members 11 in which are swiveled trunnions 12 of a guide plate 13. The guide plate is adjusted to a desirable position relative to said ladle by screws 14, one of which is placed at each end of said plate, and in a dove-tailed guide 15 of said plate, a sliding plate 16 is mounted for vertical reciprocation. 35 A socket 17 having a tapered aperture 18 is rigid with the upper end of the sliding plate 16 and the tapered lower end 19 of an angular rod 20 is passed through said aperture and secured to said socket by 40 a wedge key 21. The horizontal portion of said angular rod 20 terminates in an enlargement 22 having an elongated slot 23, through which passes the upper end 24 of 45 the ladle stopper 25, which will now be described.

The ladle stopper comprises a metal rod 50 which is provided at its lower end with a refractory plug 27 secured to the rod by a pin 28, which enters a recess in the lower end of said rod and is secured by a key 29, that passes through transverse slots in the rod and pin. The lower end of said plug is provided with a counter sunk hole 30, for the reception of the head of the pin 28, the hole being closed by refractory paste 31. Mounted on the rod, for the purpose of 55 protecting the same against the intense heat, are a series of sleeves 32, which are of refractory material and are clamped together by a nut 33, screwed on the upper

end of the rod 26. Nuts 34 engaging the upper end 24 of the stopper adjustably secure the same on the horizontal portion of the angular rod 20, and the plug 27 of the stopper is adapted to engage a nozzle or 70 spout 35 in the bottom of the ladle for the purpose of closing said nozzle.

Mounted on the exterior of the ladle 6 below the bracket 10 are a plurality of arms 36 carrying a fulcrum 37 on which is 75 pivoted a short lever 38, which when the stopper is to be raised and lowered by manual power, is adapted to be engaged by a long lever 39, shown in dotted lines in Fig. 1. The inner end of the lever 38 is pivotally connected to the lower end of a link 40, the upper end of which is pivotally connected to the sliding plate 16, and when the stopper is manually operated, as it might be in case of damage to the stopper operating mechanism, hereinafter described, the link 40 moves the sliding plate 16 either up or down as the case may be.

The mechanical power means, for raising and lowering the stopper will now be described. Secured to the exterior of the ladle and positioned at one side of the sliding plate 16, is a support 41 having a series of pairs of vertically arranged apertures 42 and a pin 43, which is secured to the support by a chain 44. This pin is adapted to pass through either pair of the aligned apertures of said support and also through an aperture in the lower end of a piston 45 of the fluid cylinder 46 for the purpose of 100 adjustably securing said piston to said support 41 and the upper end of the cylinder 46 is secured by a chain supported pin 47 to an arm 48 which extends from and is rigidly secured to the sliding plate 16. The upper end of the piston 45 is provided with cup leathers 49 and clamping rings 50 and the diameter of the piston is nearly as great as the interior of the cylinder 46, whereby a chamber 51 of large diameter is formed 105 above the piston head and a smaller chamber 52 is formed beneath the same. Carried by the crane cage 7 is a compressed fluid tank 53 which may be supplied by any suitable means (not shown) and a pipe 54 extends from the same. Secured to the upper end of said pipe is a connection 55 carrying a valve controlled by a handle 56 and a pipe 57 is secured to said connection. The free end of the pipe 57 is connected by 110 a flexible hose 58 with a nipple 59 which communicates with the chamber 52 of the cylinder 46, whereby when the valve, controlled by the handle 56 is opened, the fluid will constantly enter the chamber 52 and tend to force the cylinder 46 downwardly and with it the arm 48, the plate 16, the rod 20 and the stopper 25 to close the ladle nozzle. A three-way cock 60 having a handle 61 communicates with the connection 115 120 125 130

55 by a short pipe 62 and said cock is connected to the chamber 51 of the fluid cylinder 46 by a pipe 63 and a flexible hose 64. The operation of the above described mechanism is as follows: Assuming that the ladle 6 is in position over a mold 9 the craneman raises the handle 61 of the valve 60 admitting fluid under pressure from the tank 53 to the upper chamber 51 of the cylinder 46, raising the stopper mechanism through the connecting arm 48 and permitting the molten metal to escape through the nozzle 35. A screw 65, which is attached to the sliding plate 16, is adapted to abut against the lower end of the guide plate 13 and acts as a stop, whereby the stopper may be regulated to open the same a predetermined distance each time the cylinder 46 is raised. The area of the underside of the piston head is just large enough, under constant pressure, to close the stopper when the fluid is released from the chamber 51 and when the compressed fluid is admitted to the chamber 51, the fluid in the chamber 52 will be compressed on account of the differences in areas acted upon. To close the stopper the handle 61 is depressed, permitting the fluid from the chamber 51 to escape through an exhaust nozzle 66 to the atmosphere and a valve under the control of a handle 67 regulates the speed at which the stopper closes. The constant pressure in the chamber 52, forces the sliding plate 16 downwardly, closing the stopper and halting the flow of metal. As shown in the drawings, the cylinder 46 is placed on the ladle with its open end downward, so that in case the metal should splash over the top of the ladle, it would not prevent the cylinder from working, which would be likely if the cylinder was reversed. Should the connecting hose, pipe or air pressure fail, the valve controlled by the handle 56 can be closed, the hose uncoupled and the stopper manually operated by the lever 39 in the well known manner, until the break is repaired.

In Fig. 6, I have illustrated a modification of my fluid cylinder in which a spring 68 is provided in the small chamber 69 of the cylinder, for the purpose of closing the stopper, and in this form the pipe and hose for furnishing the small chamber 69 with compressed fluid, are obviated. In order that the fluid cylinder and its piston may be easily detached from one ladle and attached to another, to obviate the necessity of equipping each ladle with a separate cylinder, I have provided the pins 43 and 47, heretofore described, which may be quickly inserted or removed. It is very important that all molds should be filled at a uniform predetermined rate of speed, for if the molds are filled too rapidly, the gases will be entrapped, causing "piping" or unsound ingots. In the methods heretofore employed,

the ladleman guesses at the rate of speed with which each mold is filled, while with my improved mechanism each mold is filled at the same uniform speed, thereby making a more homogeneous ingot. In some cases 70 the ladle obstructs the craneman's view so that he cannot see the stream of metal and to obviate this defect, I have provided the crane cage with a periscope 70, having mirrors placed at such angles that the image 75 will be reflected to the operator, thus giving him a full view of the flowing metal and the filling mold.

What I claim and desire to secure by Letters Patent is:—

1. The combination with a portable ladle having a nozzle and a stopper for closing said nozzle, of fluid pressure operated means carried by said ladle for actuating said stopper.

2. The combination with a ladle having a nozzle and a stopper for closing said nozzle, of a fluid cylinder provided on the ladle, a piston having a head arranged in said cylinder, means connecting said cylinder and 90 said stopper, and means for introducing fluid to said cylinder above and below said piston head for raising and lowering said stopper.

3. The combination with a ladle having a 95 nozzle and a stopper for closing said nozzle, of a guide plate provided on said ladle, a sliding plate mounted in said guide plate, means connecting said sliding plate and said stopper, and fluid pressure operated means 100 carried by said ladle for raising and lowering said sliding plate and said stopper.

4. The combination with a ladle having a nozzle and a stopper for closing said nozzle, of a sliding plate arranged on said ladle, 105 an angular rod connecting said plate and said stopper, and mechanical power operated means carried by said ladle for raising and lowering said plate and said stopper.

5. The combination with a ladle having a 110 nozzle and a stopper for closing said nozzle, of a guide plate provided on said ladle, a sliding plate mounted in said guide plate, an adjustable stop arranged on one of said plates and adapted to abut against the other 115 plate for regulating the extent of travel of the stopper in one direction, means connecting said sliding plate and said stopper, and means for raising and lowering said stopper.

6. The combination with a ladle having a 120 nozzle and a stopper for closing said nozzle, of a sliding plate arranged on said ladle and provided with a socket, an angular rod having one of its ends secured to said stopper and its other end secured in said socket, and 125 fluid pressure operated means carried by said ladle for raising and lowering said plate and said stopper.

7. The combination with a ladle having a nozzle and a stopper for closing said nozzle, 130

of mechanical power operated means for actuating said stopper, said power operated means comprising a cylinder member and a piston member working in the same, means 5 for securing one of said members to said ladle and the other member to the stopper, and means for moving one of said members relative to the other member.

8. The combination with a ladle having a 10 nozzle and a stopper for closing the same, of fluid pressure operated means for actuating said stopper, and means connecting said fluid pressure operated means and said stopper, said fluid pressure operated means 15 comprising a cylinder which is secured to said connecting means, a piston provided in said cylinder and secured to said ladle, and means for introducing fluid pressure into said cylinder for raising and lowering the 20 same.

9. The combination with a crane carrying a crane cage and a ladle provided with a nozzle, a stopper for closing said nozzle, of mechanical power operated means for actu-

ating said stopper, controlling means for 25 said mechanical power operated means provided in said crane cage, and means connecting said controlling means and said mechanical power operating means.

10. The combination with a ladle having 30 a nozzle and a stopper for the same, of a fluid pressure cylinder, means connecting said cylinder and said stopper, a piston provided with a head on which said cylinder is movably mounted, said piston being secured 35 to the side of the ladle, a chamber provided in said cylinder above said piston head and a chamber of less area provided in the cylinder below said head, a compressed fluid tank, means connecting said tank and the 40 small chamber of the cylinder for introducing constant pressure to the same, means connecting said tank and said large chamber of the cylinder, and a valve arranged in said last named connecting means.

45 In testimony whereof I affix my signature.

GEORGE ALEXANDER WETTENGEL.
